INKER

John Kunz, Pittsburgh, Pa., assignor to Miller
Printing Machinery Co., Pittsburgh, Pa., a cor-
poration of Pennsylvania

Application December 10, 1940, Serial No. 369,492

11 Claims. (Cl. 101—357)

This invention relates to inkers for printing presses and the like and more particularly to an arrangement of the ink rollers and their supporting mechanism whereby important new and useful results are accomplished. This application is in part a continuation of my copending application Serial No. 137,267, filed April 16, 1937.

It has been customary heretofore to supply ink to the usual form inking rollers in such a way that upon reduction in size of the outermost form roller such roller has had to be shifted in a direction generally away from the printing cylinder in order to maintain proper cooperative relationship with the ink supplying means. Such shifting of the outermost form roller reduces the area of the form inked by all of the form rollers for a given amplitude of movement of the form and is highly disadvantageous. The form rollers are made of a composition which results in material changes in size thereof due to wear and temperature and atmospheric changes. With the ink feeding arrangements which have heretofore been employed the lower limit of the diameter of the outermost form roller has been quite limited. In other words, after the outermost form roller had had its diameter reduced to a predetermined extent it could no longer continue in use since further use of it would require moving it away from the printing cylinder to such an extent that it would not be possible to properly ink an adequate area of the form.

For example, it has been customary to supply ink to the form rollers from a fixedly mounted rotary distributing drum in rolling contact with the outermost form roller—that is, the form roller farthest removed from the printing cylinder. With such an arrangement reduction in size of the form roller in engagement with the drum necessitates adjustment of the form roller away from the printing cylinder in order that it may maintain proper cooperative relationship with the drum.

I have invented a novel inker and arrangement of inking rollers which obviate the disadvantages incident to the prior structures as above pointed out. I provide for delivering ink to a form roller by means shiftable upon changes in diameter of the form roller to maintain proper cooperative relationship therewith. Thus the necessity of moving the form roller away from the printing cylinder is obviated. Indeed when the diameters of the form rollers become materially reduced they may be moved closer together than when of their original size, which movement may be effected by moving the outermost form roller to-

ward the printing cylinder and toward the neighboring form roller. This actually increases the area of the form effectively inked by all of the form rollers for a given amplitude of movement of the form whereas previously when the worn outermost form roller had to be adjusted away from the printing cylinder the opposite effect was necessarily, although undesirably, obtained.

I provide for delivering ink to a form roller by ink delivering means including a transfer roller contacting the form roller and mounting the transfer roller so that it is shiftable to maintain contact with the form roller upon changes in size of the form roller without necessarily moving the form roller along the form, although, as above mentioned, in certain cases the form roller may be moved toward the printing cylinder whereby to increase the effectiveness of the inker when the diameter of the form rollers in an inker employing a plurality of form rollers has been materially reduced. I prefer to employ one or more transfer rollers interposed between the ink drum and the outermost form roller, although the ink drum may itself contact the outermost form roller and itself constitute a transfer roller for delivering ink directly to such form roller. In one embodiment of the invention the outermost form roller does not have direct contact with the ink drum and roller mechanism in the form of a pair of parallel rollers having rolling engagement with each other is disposed between the outermost form roller and the ink drum, one of the rollers of the pair engaging the outermost form roller and the other engaging the drum. The two rollers just mentioned are adjustable peripherally of the drum so that on a change in size of the outermost form roller they can be moved around the drum to maintain their engagement with the outermost form roller as well as with the drum. In another embodiment the ink drum itself may directly contact the outermost form roller and upon changes in size of the latter the ink drum itself, together with its associated ink distributing rollers, may be moved relatively to the form roller.

Other details, objects and advantages of the invention will become apparent as the following description of certain present preferred embodiments thereof proceeds.

In the accompanying drawings I have shown certain present preferred embodiments of the invention, in which

Figure 1 is a side elevational view, largely diagrammatic and with portions broken away,

through an inking mechanism, the press bed being shown in vertical cross section;

Figure 2 is a view similar to Figure 1 of a portion of the mechanism shown in Figure 1 but in a different position;

Figure 3 is a view generally similar to Figure 1 showing a modified construction;

Figure 4 is a view similar to Figure 3 but showing the parts in a different position; and

Figure 5 is a view similar to Figure 4 showing the parts in a still different position.

Referring now more particularly to the drawings, a printing press of the reciprocating flat bed type comprises inking mechanism indicated generally at 10, a reciprocating bed 11 and a cylinder 12 cooperating therewith. Ink is delivered to the inking mechanism 10 from the usual fountain in roller 13. A fountain ductor 14 has intermittent contact with the fountain roller 13 and a vibrating roller 15 forming part of the inking mechanism proper. Composition rollers 16 have peripheral engagement with an ink distributing drum 17. The roller 15 engages two of the rollers 16 while an additional roller 18 engages the third roller 16 and one of the two first mentioned.

The fountain ductor 14 oscillates in the usual manner from a position in which it engages the fountain roller 13 to a position in which it engages the vibrating roller 15. The ink thus transferred from the fountain to the inking mechanism proper is distributed by the cooperative action of the several rollers and the distributing drum 17.

Form rollers 19, 20 and 21 are adapted to have rolling engagement with the form mounted on the bed 11 as the latter reciprocates. The form rollers 19 and 20 obtain ink from the distributing drum 17 by means of a composition roller 22 having rolling engagement with the drum and a vibrating roller 23 having rolling engagement with the rollers 19, 20 and 22. The drum 17, incidentally, is driven in the usual manner, i. e., by a rack 24 on the bed, a pinion 25 meshing therewith, and gears 26 and 27, the latter of which meshes with a gear keyed to the shaft 28 of the drum.

The rearmost form inking roller 21 obtains its supply of ink from the drum 17 through a roller mechanism, including a composition roller 29 having rolling engagement with the drum, and a steel roller 30 having rolling engagement with the rolls 21 and 29. Neither of the rollers 21 and 30 has rolling engagement with the drum 17. The roller 30 is journaled in bearings 31 carried by arms 32 rotatably mounted on a shaft 33. Set screws 34 traversing arcuate slots 35 in the arms 32 permit the roller 30 to be secured in one of a plurality of adjusted positions. The shaft 36 of roller 30 has a pinion 37 thereon in mesh with a gear 38. A pinion 39 meshing with a rack 40 on the bed drives the gear 38. The pinions 25 and 39 and the gears 26, 27 and 38 are all journaled on shafts carried in the frame of the press in the usual manner, as are also the various composition and steel rollers making up the inking mechanism.

It will be understood from the foregoing description that ink passes from the distributing drum 17 to the form rollers 19 and 20 by way of the rollers 22 and 23. Similarly, ink passes to the form roller 21 by way of rollers 29 and 30. A steel roller 41 has rolling engagement with the form rollers 20 and 21 and insures uniform ink distribution therebetween.

Figure 1 of the drawings shows the rollers 29 and 30 adjusted for the maximum size and spacing of the form inking rollers. If changing atmospheric conditions or wear should cause a reduction in the size of the form inking rollers to the extent indicated in Figure 2, the rollers 19 and 20 are adjusted closely together so as to maintain rolling contact with the roller 23. The rearmost form roller 21 is also adjusted closer to the roller 20. The rollers 29 and 30 are then adjusted so that the roller 30 has engagement with the roller 21 and the roller 29 with the drum 17. When the desired adjustment of the rollers 29 and 30 has been effected, the set screws 34 are tightened to maintain the proper adjustment.

By means of the arrangement described in the foregoing, the desired close spacing of the form inking rollers is maintained at all times. It is unnecessary to retract the roller 21 to an extent such that it engages the drum 17 after shrinking due to changing atmospheric conditions or reduction in size due to wear, as was the case heretofore. The close spacing of the form rollers is desirable for the reason stated above, i. e., that such arrangement permits the uniform inking of the maximum area on the form.

In Figure 3 there is shown a modified structure generally similar to that of Figures 1 and 2 but eliminating the rollers 29 and 30. In Figure 3 parts corresponding to the parts designated in Figures 1 and 2 are designated by the same reference numerals as appear in Figures 1 and 2 but each with a prime affixed. The rearmost or outermost form roller 21' of Figure 3 has direct contact with the drum 17'. The drum is driven through gearing just as in Figure 1 but is differently mounted. A frame 42 is pivotally supported upon the shaft 43 which carries the gear 27'. The frame 42 has a handle 44 through which it may be turned about the axis of the shaft 43. The frame also has an arcuate slot 45 through which passes a bolt 46. The bolt 46 also passes through a circular hole in the main frame of the inker of proper size to receive it without substantial lost motion and a nut 47 is applied to the bolt. When the frame 42 is brought to a desired adjusted position the nut 47 is tightened upon the bolt 46 so as to hold the portion of the frame about the arcuate slot 45 against the main frame and thereby hold the frame 42 in the desired adjusted position. The drum shaft 28' is mounted in the frame 42. Likewise the rollers 14', 15', 16' and 18' are carried by the frame 42 and adapted to cooperate with the drum 17', as clearly shown in Figure 3.

Figure 4 shows the same structure as is shown in Figure 3 but with the form rollers 19', 20' and 21' of materially reduced diameter. Due to such material reduction in diameter the form rollers 19' and 20' of Figure 4 have been moved closer together as compared with the relative positions of these rollers as shown in Figure 3 so as properly to cooperate with the roller 23', but the roller 21' has not been moved either toward or away from the printing cylinder relatively to the position it occupies in Figure 3. In order to properly cooperate with the relatively small form roller 21' the frame 42 has been swung in the clockwise direction about the axis of the shaft 43 to maintain the drum 17' in contact with the roller 21'. The other rollers carried by the frame 42 naturally assume their proper cooperative positions relatively to the drum 17' as clearly shown in the drawings.

Thus proper cooperative relationship can be

maintained between the ink supplying means and the outermost form roller despite changes in diameter of the latter without moving it toward the printing cylinder. As shown in Figure 4, the outermost form roller need not be moved at all unless desired.

Figure 5 is the same as Figure 4 except that Figure 5 shows the form roller 21' moved toward the left so as to be closer to the printing cylinder and closer to the cooperating form roller 20'. The frame 42 has been swung down to a position lower than that shown in Figure 4 to bring the drum 17' into proper cooperative relationship with the roller 21'. Thus not only is it not necessary to move the outermost form roller farther away from the printing cylinder upon reduction in size of such roller, but it can actually be moved toward the printing cylinder without adversely affecting the cooperative relationship therewith of the ink supplying mechanism and with the added advantage of more effectively inking the form.

While I have shown and described certain present preferred embodiments of the invention it is to be distinctly understood that the invention is not limited thereto but may be otherwise variously embodied within the scope of the following claims.

I claim:

1. The combination in a printing press with a reciprocating flat bed carrying a printing form, of inking mechanism for the latter including a plurality of form rollers adapted to engage said form, the permissible size of the form depending on the position of the rearmost form roller relative to the stroke of the bed, a distributing drum for supplying ink to said form rollers, a pair of auxiliary rollers in contact with each other, one engaging said drum and the other engaging said rearmost form roller, and means mounting at least one of said auxiliary rollers for movement relative to the drum and rearmost form roller to maintain contact with the latter despite shrinkage thereof without shifting the rearmost form roller along the path of the bed and thereby reducing the permissible size of the form.

2. The combination in a printing press with a reciprocating flat bed carrying a printing form, of inking mechanism for the latter including a plurality of form rollers adapted to engage said form, the permissible size of the form depending on the position of the rearmost form roller relative to the stroke of the bed, a distributing drum for supplying ink to said form rollers, roll mechanism having engagement with said rearmost form roller and said drum and means mounting said mechanism for movement toward and from said rearmost form roller whereby to maintain contact with the latter despite shrinkage thereof without shifting the rearmost form roller along the path of the bed and thereby reducing the permissible size of the form.

3. The combination in a printing press with a reciprocating flat bed carrying a printing form, of inking mechanism for the latter including a plurality of form rollers adapted to engage said form, the permissible size of the form depending on the position of the rearmost form roller relative to the stroke of the bed, a distributing drum for supplying ink to said form rollers, a pair of auxiliary rollers in contact with each other, one engaging said drum and the other engaging said rearmost form roller, and means mounting at least one of said auxiliary rollers for substantially horizontal movement relative to the drum

and rearmost form roller, to maintain contact with the latter despite shrinkage thereof without shifting the rearmost form roller along the path of the bed and thereby reducing the permissible size of the form.

4. Inking mechanism for a printing press comprising a form roller subject to changes in size, a cylindrical member mounted to rotate about a fixed axis for delivering ink, transfer means for transferring ink from said cylindrical member to said form roller, said transfer means comprising a plurality of rollers at least one of which contacts said form roller and at least one of which contacts said cylindrical member, and means for mounting said transfer means whereby at least one of the rollers thereof is shiftable to maintain contact with said form roller upon changes in size of said form roller.

5. Inking mechanism for a printing press comprising a plurality of form rollers at least one of which is subject to changes in size, a cylindrical member mounted to rotate about a fixed axis for delivering ink, transfer means for transferring ink from said cylindrical member to said last mentioned form roller, said transfer means comprising a transfer roller contacting said last mentioned form roller and at all times out of contact with the remaining form roller or rollers, and means for mounting said transfer roller whereby the same is shiftable to maintain contact with said last mentioned form roller upon changes in size of said last mentioned form roller.

6. Inking mechanism for a printing press comprising a frame, a plurality of form rollers subject to changes in size, ink delivering means, transfer means for transferring ink from said ink delivering means to an outer form roller, said transfer means comprising a cylindrical member contacting said last mentioned form roller, means for mounting said cylindrical member whereby the same is shiftable to maintain contact with said last mentioned form roller upon changes in size of said last mentioned form roller, the remaining form roller or rollers being positioned out of the path of said cylindrical member when the same is so shifted, and means fastening said mounting means to the frame in desired adjusted positions to fixedly position the same to insure continuance of contact between said cylindrical member and said last mentioned form roller to deliver ink to said last mentioned form roller until said last mentioned form roller undergoes substantial diminution in size.

7. Inking mechanism for a printing press comprising a frame, a plurality of form rollers subject to changes in size, a cylindrical member mounted to rotate about a fixed axis for delivering ink, transfer means for transferring ink from said cylindrical member to an outer form roller, said transfer means comprising a transfer roller contacting said outer form roller, means for mounting said transfer roller whereby the same is shiftable to maintain contact with said outer form roller upon changes in size of said outer form roller, the remaining form roller or rollers being positioned out of the path of said transfer roller when the same is so shifted, and means fastening said mounting means to the frame in desired adjusted positions to fixedly position the same to insure continuance of contact between said transfer roller and said outer form roller to deliver ink to said outer form roller until said outer form roller undergoes substantial diminution in size.

8. Inking mechanism for a printing press com-

prising a frame, a plurality of form rollers subject to changes in size, an ink supply, ink delivering means for delivering ink from the ink supply to an outer form roller, said ink delivering means including a transfer roller contacting said outer form roller and in ink delivering relation with said ink supply for delivering ink from the ink supply to said outer form roller, means for mounting said transfer roller whereby the same is shiftable relatively to said ink supply to maintain contact with said outer form roller upon changes in size of said outer form roller while continuously maintaining ink delivering relation with said ink supply without necessitating moving said outer form roller along the form, the remaining form roller or rollers being positioned out of the path of said transfer roller when the same is so shifted, and means fastening said mounting means to the frame in desired adjusted positions to fixedly position the same to insure continuance of contact between said transfer roller and said outer form roller to deliver ink to said outer form roller until said outer form roller undergoes substantial diminution in size.

9. Inking mechanism for a printing press comprising a frame, a plurality of form rollers subject to changes in size, an ink supply, ink delivering means for delivering ink from the ink supply to an outer form roller, said ink delivering means including a transfer roller contacting said outer form roller and in ink delivering relation with said ink supply for delivering ink from the ink supply to said outer form roller, a pivoted support for mounting said transfer roller whereby upon pivoting of said support said transfer roller is shiftable relatively to said ink supply to maintain contact with said outer form roller upon changes in size of said outer form roller while continuously maintaining ink delivering relation with said ink supply without necessitating moving said outer form roller along the form, the remaining form roller or rollers being positioned out of the path of said transfer roller when the same is so shifted, and means fastening said mounting means to the frame in desired adjusted positions to fixedly position the same to insure continuance of contact between said transfer roller and said outer form roller to deliver ink to said outer form roller until said outer form roller undergoes substantial diminution in size.

- 5 10. Inking mechanism for a printing press comprising a frame, a plurality of form rollers subject to changes in size, ink delivering means, transfer means for transferring ink from said ink delivering means to an outer form roller, said transfer means comprising a large diameter ink drum for working up the ink contacting said last mentioned form roller, means for mounting said ink drum whereby the same is shiftable to maintain contact with said last mentioned form roller upon changes in size of said last mentioned form roller, the remaining form roller or rollers being positioned out of the path of said ink drum when the same is so shifted, and means fastening said mounting means to the frame in desired adjusted positions to fixedly position the same to insure continuance of contact between said ink drum and said last mentioned form roller to deliver ink to said last mentioned form roller until said last mentioned form roller undergoes substantial diminution in size.

- 10 11. Inking mechanism for a printing press comprising a frame, a plurality of form rollers subject to changes in size, an ink supply, ink delivering means for delivering ink from the ink supply to an outer form roller, said ink delivering means including a large diameter ink drum for working up the ink contacting said outer form roller and in ink delivering relation with said ink supply for delivering ink from the ink supply to said outer form roller, a pivoted support for mounting said ink drum whereby upon pivoting of said support said ink drum is shiftable relatively to said ink supply to maintain contact with said outer form roller upon changes in size of said outer form roller while continuously maintaining ink delivering relation with said ink supply without necessitating moving said outer form roller along the form, the remaining form roller or rollers being positioned out of the path of said ink drum when the same is so shifted, and means fastening said mounting means to the frame in desired adjusted positions to fixedly position the same to insure continuance of contact between said ink drum and said outer form roller to deliver ink to said outer form roller until said outer form roller undergoes substantial diminution in size.

JOHN KUNZ.
